DUST-RECEIVING RECEPTACLE FOR MOPS

John O. Barkl, Washington, D. C.

Application June 4, 1954, Serial No. 434,516

8 Claims. (Cl. 15—257)

The present invention relates to dust-receiving receptacles for handled mops and the like and comprises an improvement of the receiver which forms the subject of my U. S. Patent No. 2,431,452, issued November 25, 1947.

The receptacle provided by the present invention constitutes a bag which can be collapsed for storage in a space of small compass when not in use and which can be readily expanded to provide a capacious closed chamber into which the head of a mop or the like may be inserted and shaken to dislodge adhering dust therefrom for collection in the chamber.

Housewives and others who use dust mops and the like to clean the floors of rooms experience considerable difficulty and annoyance in connection with the cleaning of the mops during use. Efficient cleaning of most rooms requires that the cleaning operation be interrupted one or more times, even when the room being cleaned is relatively small, to free the mop head of accumulated dust. It is frequently not convenient to carry the mop to a more or less distant dust receiver, and there are obvious objections to shaking the mop out of an open window.

My prior patent discloses a dust receiver which is substantially closed when disposed in position for use but which is provided with a narrow lengthwise slit in an upright side wall which may be opened for insertion of the mop head, with the mop handle projecting through the slit and relatively snugly engaged by flexible material defining the slit, so that the handle may be shaken manually, thereby dislodging the dust from the mop head, for settling and collection in the bottom of the receptacle.

The present receptacle similarly provides a substantially closed chamber having a slotted lengthwise opening in a vertical side wall, and cooperates in generally the same manner with the head and handle of the mop.

Important distinctions between the present improvement and the previous device reside in the structure of the receptacle and in the means for suspending it in use.

Broadly speaking, the improvement consists in eliminating the rigid framework that characterized the bag forming the previous receptacle and in providing the new entirely limp and flexible bag with means for suspending it from the back of a chair instead of from the knobs of a door as in the case of the previous bag.

General objects of the present invention are to improve the hanging or suspending arrangement of the bag, to simplify its construction and materially reduce its cost of manufacture, and to decrease the space occupied by the bag when collapsed for storage, all without in any way reducing the efficiency of the bag in the performance of its intended functions.

With the foregoing and other objects in view, as will be evident from the following description, a preferred form of embodiment of the invention is disclosed by the accompanying drawings in which:

Figure 1 is a perspective view of the preferred embodiment of the invention disposed in operative position on the back of a chair, with a mop head inserted in position to be shaken free of its accumulated dust;

Fig. 2 is a similar perspective view taken from a different angle;

Fig. 3 is a vertical sectional view taken substantially centrally through the bag and the supporting chair; and

Fig. 4 is a cross sectional view taken through the bag on the line 4—4 of Fig. 3.

Referring to these drawings, the invention comprises

2

essentially a large bag 1 which may be made of heavy kraft paper or the like, and may be constructed in the manner of the large bags used in stores for the packaging of miscellaneous collections of groceries and the like sold to retail purchasers. Such a bag is best made of a single sheet of heavy paper or the like cut to an appropriately shaped blank and then folded and secured at certain overlapping margins to provide a generally rectangular front wall 2, a similar back wall 3, a pair of side walls 4, 4 and a bottom wall 5. All the walls are of rectangular shape; the front and back walls are of equal shape and size and are parallel to each other when the bag is opened; and the two side walls are of equal size and shape and are parallel to each other when the bag is opened. The back wall 3 may include overlapped margins 6 adhesively secured together, and other margins may be overlapped and adhesively secured together in the bottom wall 5. The side walls 4, 4 are centrally vertically creased, as shown at 7, 7, so that the bag can be collapsed by folding the side walls inwardly along the crease lines, while at the same time folding the bottom wall 5 upwardly through the medium of downwardly diverging side wall crease lines 8, 8 and a back wall transverse crease line 9, thus bringing the front and back walls into flat engagement with each other and turning the bottom wall up into engagement with the back wall. All the foregoing is in accordance with standard paper bag making practice and is believed to require no further explanation.

In this connection it may be noted that the bag as thus far described may be otherwise made and be of specifically different construction from the above suggested preferred construction, as long as it is devoid of supporting framework and has no rigid parts or elements that would prevent collapse and/or folding into a minimum volume.

As has been stated, the bag walls, both front and back, as well as the two side walls, extend upwardly to a normally open top opening. In use this top opening is closed. In a bag construction of the preferred type, closing can be readily effected by bringing the front and back walls together into contact with each other, with the upper portions of the two side walls tucked inwardly by folding along the longitudinal creases 7, and then turning the engaged margins of the front and back walls over on each other, preferably through two or more turns, into the relationship shown in Figs. 1, 2 and 3. This closed relationship may be maintained by operation of any suitable catch or fastener, such as the conventional paper clips shown at 22.

A short tape 10 may be securely fastened at one end to one of the bag walls (or to the pocket-forming sheet attached thereto and presently to be described), with an eyelet in its other end for hanging the bag when not in use. Of course any other appropriate types of fastener and hanging means may be employed.

The front wall 2 of the bag is provided with a slotted opening 12 through which the head 13 of a mop may be inserted, with the handle 14 protruding, and with the margins of the slotted opening tending to hug the handle, so that the handle may be manually shaken in a vertical plane without involving any very material opening of the slit, as will be understood from the showings in Figs. 1 and 3.

The slit is best formed in the following manner: The paper or equivalent material of the bag wall 2 is cut out to provide a relatively large oblong opening extending lengthwise through the major portion of the wall. Two strips of flexible sheet material, preferably a strong sheet plastic like vinyl or polyethylene film, are folded lengthwise on themselves to provide a pair of double ply closure members 15, each somewhat wider and longer than the oblong opening. In the alternative, flattened tubing of similar material may be substituted for folded-over flat sheets to form the members 15. These closure members are then secured to the sides, bottoms and tops of the margins of the opening, as shown at 16 in Fig. 1, preferably by reinforcing binding strips of paper or the like 17, stitched around the margins of the members so as to form a rectangular frame which covers the top, bottom and outer side of each of the strips 15. This

70
75
80

frame is secured to the bag wall material 1 surrounding the oblong opening by adhesive. The bindings, it will be noted, cover and conceal all raw free edges of the strips 15 (said raw free edges being, at the top, bottom, and outer side, in the case of folded-over sheets, and being confined to the top and bottom if tubing be used). The arrangement is such that each of the folded strips (or flattened tubes) 15 very completely overlaps the other, with a folded edge exposed, so that the mop head may be inserted behind the outermost strip, between it and the inner strip, and be thus introduced into the bag. As has been explained, the handle 14 protrudes through the slotted opening, so that it can be shaken up and down with a minimum of displacement of the strips 15, to dislodge the dust from the mop head 13 and cause it to descend and be collected in the bottom of the bag.

In order to hang the bag in operative position for the foregoing use, the back wall 3 of the bag has secured to its upper portion three of the four marginal edges of a generally rectangular sheet of paper or the like 18. The bottom edge of the sheet 18 is unattached to the wall 3 except at its extreme lateral edges, so that the sheet forms with the back wall a downwardly opening pocket 19 which may be slipped over the back 20 of a chair 21, as shown in Figs. 2 and 3. The pocket 19 is proportioned properly to fit the back of any usual type of kitchen or dining room chair or other chair of generally similar style, and the bag is made of proper length to have its bottom wall spaced somewhat above the floor when the pocket is fitted down completely on the chair back, all as shown in Figs. 1, 2 and 3.

It is a simple matter to hang the closed bag in the manner above described and to spread its back and front walls apart so as to expand the walls to provide a capacious chamber within the bag. Indeed, it is only necessary that the bag be hung in position as explained, without performing any special wall-expanding operation, because insertion of the mop head through the slotted opening 12 will start expanding the walls, and vertical shaking of the mop will complete the expansion.

It will be understood that the bag is carried from room to room as the cleaning operation proceeds and is hung on chairs in the several rooms. The mop head is inserted and shaken as often as required. On completion of the cleaning operation, or after the completion of several such operations, whenever the accumulation of dust in the bottom of the bag appears to require it, the bag is emptied by opening its top and dumping the dust therefrom into any suitable waste receptacle.

The invention has been described in terms of the foregoing preferred form of embodiment, but it is believed to be evident that various changes may be made in the details of the disclosed construction without departing from the spirit of the invention as defined by the broader of the appended claims.

I claim:

1. A dust-receiving receptacle for handled mops comprising a sheet of flexible material folded on itself with certain of its margins secured in overlapping position to form a collapsible bag having a closed bottom and an enclosing wall structure upstanding from said bottom including front and back walls, said front wall having overlapping plies of flexible sheet material defining a normally closed lengthwise slotted opening and being separable by a mop head inserted through the opening with the mop handle projecting to the outside for manual shaking movement with the plies tending to keep the opening closed about the handle, the upper portion of the

back wall being provided with a downwardly open pocket adapted to be fitted over the back of a chair to hang the bag, and means for holding the front and back walls together at their top edges to keep the bag closed.

5 2. A dust-receiving receptacle as claimed in claim 1, in which the overlapping plies defining the slotted opening are separate from the named sheet of flexible material and are secured thereto at their margins.

10 3. A dust-receiving receptacle as claimed in claim 1, in which the front wall is provided with an oblong cut-out and the overlapping plies of flexible material are secured to said wall at the margins of said cut-out.

4. A dust-receiving receptacle as claimed in claim 1, in which the bag is formed of a sheet of paper and the overlapping plies defining the slotted opening are formed of sheet plastic material of greater strength than said paper.

20 5. A dust-receiving receptacle as claimed in claim 1, in which said pocket comprises a sheet of flexible material having its top and side margins secured to the back wall of the bag.

25 6. A dust-receiving receptacle as claimed in claim 1, in which the front wall is provided with an oblong cut-out and the overlapping plies of flexible material defining the slotted opening comprise a pair of strips each folded on itself to provide a double thickness with the free edges secured to the front wall material at the longitudinal margins of the cut-out and with the folded edge extending laterally beyond the folded edge of the other strip.

30 7. A dust-receiving receptacle as claimed in claim 1, in which the front wall is provided with an oblong cut-out and the overlapping plies of flexible material defining the slotted opening comprise a pair of strips each folded on itself to provide a double thickness with the free side edges secured to the front wall material at the longitudinal margins of the cut-out and with the end edges secured to the front wall material at the top and bottom margins of the cut-out and with the folded side edge extending laterally beyond the folded edge of the other strip.

35 8. A dust-receiving receptacle for handled mops comprising a collapsible paper bag having a bottom wall and front, back and side walls extending upwardly therefrom and terminating in a normally open top opening, means for holding the front and back walls folded over on each other with the upper portions of the side walls tucked inwardly to close the top opening, a ply of sheet material secured at its top and sides to the upper portion of the back wall to provide a downwardly open pocket adapted to be fitted over the back of a chair to hang the bag, and the front wall being provided with overlapping plies of flexible sheet material defining a longitudinal slit through which a handled mop head may be inserted into the bag with the handle projecting to the outside for manual shaking movement with the plies tending to keep the slit closed about the handle.
